[57] CLAIM

The ornamental design for blood coagulation analyzer, as shown and described.

DESCRIPTION

FIG. 1 is a perspective view of a blood coagulation analyzer; showing my new design; in closed condition;

FIG. 2 is a perspective view thereof, in open condition;

FIG. 3 is a front elevational view thereof;

FIG. 4 is a top plan view thereof;

FIG. 5 is a side elevational view thereof, the opposite side elevational view being identical;

FIG. 6 is a top plan view thereof, in closed condition; and, FIG. 7 is a bottom plan view thereof.

The broken line showing of the elements in FIGS. 6 and 7 is for illustrative purposes only and forms no part of the claimed design.
